UNITED STATES PATENT OFFICE.

HENRY L. JACOBS AND THOMAS H. STAGG, OF COLUMBUS, OHIO, ASSIGNORS
TO FREDERICK C. AUSTIN, OF CHICAGO, ILLINOIS.

ROAD-SCRAPER.

SPECIFICATION forming part of Letters Patent No. 393,434, dated November 27, 1888.

Application filed July 10, 1888. Serial No. 279,575. (No model.)

To all whom it may concern:

Be it known that we, HENRY L. JACOBS and THOMAS H. STAGG, both citizens of the United States, residing at Columbus, in the county of 5 Franklin and State of Ohio, have invented a certain new and useful Improvement in Road-Scrapers, of which the following is a specification.

In a road scraper characterized by our invention the scraper-blade is arranged so that it may be shifted bodily in a direction transversely to the line of progression, and hence be thrown or shifted toward either side of the road, and as a means for attaining such end 10 the scraper-blade has a shifting connection with the hangers or suspending devices, which are capable of vertical adjustment independently of one another, whereby by adjusting one of the hangers so as to lift the scraper-blade at one end it will as a result thereof automatically shift in the direction of its lower end. As a simple and exceedingly powerful means for either raising the scraper-blade clear 15 of the ground or lowering and forcing the scraper-blade into the ground, the hand-levers, which can be operated by an attendant standing upon the machine, are connected with the scraper-blade through the medium of hangers, each involving the principle of an elbow-joint 20 or toggle-lever, in which way the employment of a spring or springs for floating the scraper-blade and assisting the manual operation of raising the scraper-blade can be entirely dispensed with, in addition to which the scraper-blade 25 can with comparatively little effort be forced to any desired depth into the ground and so held as long as may be necessary. The toggle-levers constitute efficient independent hangers, which can in effect be shortened or 30 vertically adjusted, for the purpose of raising either end of the scraper-blade, and hence, in addition to their utility, irrespective of the side shift of the scraper, the feature of said compound or toggle levers, in combination with 35 the shifting scraper-blade, constitutes a further matter of improvement. It is, however, understood that the distinctive feature of a scraper-blade arranged so that when raised at one end it will shift toward its lower end, or 40 toward the side of the machine whereat its

temporarily lower end may be, is not dependent upon the particular construction of hangers, since various forms or constructions of adjustable hangers or suspending devices could obviously be employed in place of hangers 55 formed by toggle or compound levers. A road-scraper involving our invention also comprises certain details of construction constituting further matters of improvement and serving to increase the general utility and efficiency of the machine, as hereinafter fully set forth.

In the drawings, Figure 1 represents in side elevation a road scraper embodying the principles of our invention. Fig. 2 represents a 60 top plan view of the middle portion of the same. Fig. 3 represents a transverse section taken on a plane indicated by line 3 3, Fig. 1. Figs. 4 and 5 represent certain details.

The scraper-blade A is suitably connected 70 with a laterally-swinging draft-bar, B, which, by reason of its lateral swing, permits a bodily shift or swing toward either side of the machine.

To the hangers by which the scraper-blade 75 can be raised and lowered is attached a bar, C, arranged transversely to the length of the machine and adapted to serve as a track for the sheaves or rolls D on a couple of bearings or brackets, d, with which the scraper-blade 8c is suitably connected. By such arrangement, when either one of the hangers is raised or adjusted, so as to raise one end of the scraper-blade, (for example, as in Fig. 3,) the inclination of the scraper-blade will cause it to 85 move toward the side of the machine whereat its lower end will be found, the rolling of the rolls along the bar, while serving to obviate friction and permitting the scraper-blade and its connections with the rolls to readily run 90 down the incline, being in effect a shifting or sliding connection between the scraper-blade and the rod, it being, however, highly desirable to provide rolls in the shifting connection, so as to lessen friction and allow the scraper 95 to shift freely by gravity when lifted at one end. As a preferred matter of detail, however, the scraper-blade is suitably connected with the bearings d, having rolls arranged to run upon the rod that is attached to the ad- 100

justable hangers or suspension devices, since to attach the rolls to the suspension devices and permit the bar to move along the rolls would necessitate the employment of an objectionably long bar.

While no limitation is herein placed upon the mode of connecting the scraper-blade with rolls D, it may be observed that as a simple expedient the bearings d, in which said rolls are journaled, are secured to the circle E, and the part-circular bar F, having downwardly-bent end portions that are attached to the scraper-blade, is adjustably connected with the circle E by a cross-bar, G, whereby the scraper-blade can be turned horizontally about the center of the circle, and hence be set more or less oblique to the line of progression.

The hand-levers H are fulcrumed upon the body-frame I of the machine and arranged within convenient reach of an attendant standing upon the rear platform. These hand-levers are connected with the compound or toggle levers K by means of links or connecting-rods L, having their rear ends pivotally attached to the hand-levers and their forward ends pivotally attached to the toggle-levers at the joints in the latter.

Each toggle or compound lever comprises two pivotally-connected links, whereof the one link, k, is at its upper end pivotally attached to one of a pair of brackets, M, while the other link, k', is connected to one of the ends of the bar C. By the foregoing arrangement the attendant can readily raise and lower the scraper and also force the scraper down into the ground, it being observed that in illustration of the great power which can be exerted by the attendant he can at will operate either hand-lever, so as to raise one of the rear wheels entirely clear of the ground, and hence the use of a jack for lifting the rear corners of the machine when it becomes necessary to apply axle-grease to the axles is avoided. In fact, by operating both hand-levers both rear wheels can at one time be raised from the ground, although as a matter of practice the raising of but one rear wheel at a time is necessary.

In order to prevent the rod or bar C from binding against the hangers when either or both hand-levers are swung back for the purpose of raising the scraper-blade, each roll D is flanged along its rear end, as at d', Figs. 4 and 5, and the roll flared toward the flange, in which way the free travel of the rod C along the rolls will at all times be insured.

Each bracket is preferably made of an inverted-V shape; but, regardless of its particular shape, the bracket is adapted to permit the upper link of the toggle or compound lever allotted to it to be adjustably connected with the bracket. As a simple mode of construction, each bracket is at its upper end provided with a bent arm or top portion, m, having a line of perforations for a bolt, by which the link can be adjustably pivoted to the bracket,

it being understood that while the link could be pivoted to the outer downwardly-bent portion of said upper part, m, of the bracket, it is preferably pivoted between the two sides of said bent portion. The foregoing construction of bracket, while light and simple, is exceedingly strong, and by adjustably attaching the links k to the brackets, the points from which the toggle or compound levers are suspended can be shifted in height.

What we claim as our invention is—

1. In a road-scraper, the combination, with a couple of vertically-adjustable scraper-blade-suspending devices operative independently of one another to lift the scraper at either end, of a cross-rod supported by said suspending devices, and the scraper-blade suspended from the rod by a shifting connection, permitting the scraper to shift toward either end of the same, whereby by raising the rod at one end the scraper-blade can shift endwise by gravity, substantially as set forth. 75

2. In a road-scraper, the combination, with the scraper-blade and a couple of hangers which can be independently operated to raise or lower either or both ends of the scraper-blade, of a rod connecting the two hangers, and rollers connected with the scraper-blade and supported upon said rod, substantially as and for the purpose set forth. 90

3. In a road-scraper, the combination, with the scraper-blade-suspending hangers, of the scraper-blade, the rod C, attached to the hangers, and the rolls arranged upon the rod and journaled in bearings d, substantially as set forth. 100

4. In a road-scraper, the combination, with the scraper-blade, of the hangers which serve to suspend the scraper, comprising each an upper link, k, and a lower link, k', pivotally connected to form an elbow-joint which is hung at its upper end, whereby the scraper can be raised and lowered and its height determined by the closing and opening of the elbow-joint, substantially as set forth. 105

5. In a road-scraper, the combination, with the scraper-blade, of the toggle-levers K, the hand-levers H, and the links connecting the hand-levers with the toggle-levers, substantially as described. 115

6. In a road-scraper, the combination, with the toggle or compound levers, of the rod attached to the said levers, and the scraper-blade connected with rolls which are supported upon said rod, substantially as described. 120

7. In a road-scraper, the combination, with the toggle or compound levers, and means, substantially as set forth, for operating the same, of the rod attached to the said levers, and the scraper connected with rolls D, which are arranged upon said rod, substantially as described. 125

8. The brackets arranged upon the body-frame and constructed with the upper bent portions, m, to which the links of the hangers 130

for suspending the scraper-blade are attached, substantially as and for the purpose described.

9. The combination, with the rod C, attached to a hanger, K, and link-connections between 5 said hangers and the hand-levers, of the scraper-blade provided with flanged rolls D, which rest upon the rod, the flanges of said rolls being arranged to prevent binding when either

or both hand-levers may be swung back to lift the scraper, substantially as set forth.
